J. HAHN

PUMP

Filed July 31, 1923

UNITED STATES PATENT OFFICE.

JOHN HAHN, OF LOS ANGELES, CALIFORNIA.

PUMP.

Application filed July 31, 1923. Serial No. 654,895.

To all whom it may concern:

Be it known that I, JOHN HAHN, a citizen of the United States, residing at Los Angeles, in the county of Los Angeles and State of California, have invented a new and useful Pump, of which the following is a specification.

This invention relates to pumps of the type employed in discharging liquids from wells and is especially serviceable in deep water and oil wells.

In many wells a very fine sand present in the liquid being pumped tends to cause excessive wear of the plunger and working barrel, as it is very difficult to prevent the entrance of such sand between the plunger and working barrel.

An object of this invention is to prevent to a great degree the entrance of this sand between the working barrel and plunger.

Another object is to make provision for discharge of the sand from the pump when said sand accumulates to such a degree as to "sand up" the pump, as it is generally termed.

A further object is to provide for tightly packing the working barrel within the pump tubing at both ends of said barrel to prevent the entrance of sand in the space therebetween, and at the same time permit of ready pulling of the working barrel.

A further object is to provide a pump which may have a main standing valve and an auxiliary standing valve, the auxiliary standing valve being omitted in some instances, it being used in event of there being a great quantity of gas produced with the liquid or in event of the main standing valve being put out of commission by an accumulation of sand.

Another object is to make provision for withdrawing the inserted part of the pump from the pump tubing without disturbing said tubing.

Another object is to provide for holding the working barrel in place by a frictional lock.

Another object is to make provision for holding the plunger straight just above the working barrel to prevent such wear at the upper end of the working barrel as would permit of the entrance of a relatively large amount of sand between the working barrel and plunger, thus causing relatively quick deterioration of the pump. In the pumping operation it is impossible with ordinary

pumps to prevent wear at the upper end of the working barrel because of the lateral movement of the sucker rods upon the down stroke thereof, the sucker rods springing out of a line coinciding with the axis of the plunger and, consequently, producing unequal radial pressure of the plunger in the working barrel.

A further object is to provide a valve cage having its bore or valve chamber for its entire circumference of considerably larger diameter than the valve ball so that said ball can freely roll to one side of the axis of the valve cage to permit of the free flow of liquid therethrough.

Other objects and advantages will appear in the subjoined detailed description.

The accompanying drawings illustrate the invention:

Figure 1 is a broken sectional elevation of a pump constructed in accordance with the provisions of this invention, the upper and lower sections thereof being placed side by side to shorten the view.

Fig. 2 is an enlarged sectional elevation of the middle portion of the upper section of the pump in Figure 1.

Fig. 3 is an inverted plan section on the line indicated by 3—3, Figure 2.

Fig. 4 is an enlarged sectional elevation of the lower portion of the pump omitting the upper standing valve and showing an imperforate tubular seat member on the lower end of the working barrel in place of a perforate member as in Fig. 1.

Referring to the drawings, pump tubing is indicated at 11 and is constructed in the usual manner of screw-threaded sections connected by couplings 12. The pump tubing 11 has a perforate section 13, the perforations being indicated at 14.

Within the lower portion of the pump tubing is a main standing valve cage 15 having a valve seat 16 for a ball valve 17, the bore 100 or chamber of the valve cage 15 is of substantially greater diameter at all points than the valve ball 17 and the wall of said chamber is curved outwardly and upwardly from the valve seat 16 as indicated at 19, 105 thus affording ample clearance around the valve ball so that said valve ball can move out of axial alignment with the seat to permit ready flow of liquid through the valve cage. The curved character of the lower 110 portion of the walls of the chamber 18 causes the valve ball to instantly roll into the closed

position on the seat 16 as soon as the upward flow of liquid through the valve cage ceases.

The valve cage 15 is yieldingly supported upon a coil spring 20 which rests upon an internal annular shoulder 21 of the pump tubing, said shoulder in this instance being formed by the upper end of the tail pipe or anchor 22 of the pump. To prevent sand and liquid reaching the spring 20 and clogging said spring, a bushing 23 forms the inner wall of the chamber 24 in which the spring 20 is housed, the pump tubing forming the outer wall of said chamber. The bushing 23 is in sliding engagement with the tail pipe 22 and the upper end of said bushing is screw-threaded into the lower end of the valve cage 15 against the valve seat 16 to hold said valve seat in place.

The valve cage 15 constitutes a pump seat-forming member, the upper end of the valve cage providing a seat 25 for either a perforate tubular member 26 shown in Figure 1 or an imperforate tubular member 27 shown in Figure 4. The perforations of the tubular member 26 are indicated at 28 and admit fluid, that has entered the perforations 14, to the interior of the tubular member 26 in some instances, or, in other instances, permit the escape of gas that may have entered the tubular member 26 through the valve cage with the liquid that flows upwardly into the tail pipe 22. The seat 25 and lower ends of the members 26, 27 inserted therein are tapered inwardly and downwardly so as to form a leakproof joint between the standing valve and member 26 or 27, as the case may be, and at the same time permit of the member 26 or 27 being readily disconnected from the valve cage. Preferably the perforate section 13 of the pump tubing is of considerably greater diameter than the tubular member 26 so as to form a chamber 29 therebetween.

The tubular member 26 serves to connect the pump seat 25 with an upper or auxiliary standing valve cage 30, the upper end of the member 26 being screw-threaded into the lower end of the valve cage 30 against the valve seat 31 of said cage so as to hold said valve seat in place. Adapted to close upon the valve seat 31 is a valve ball 32. The bore or valve chamber 33 is constructed substantially the same as the valve chamber 18 hereinbefore described and, therefore, further detailed description of the valve chamber 33 is unnecessary. The valve cage 30 is connected by screw-threads with the lower end of a working barrel 34 in which reciprocates a valved plunger 35. The lower or intake plunger cage, valve ball and valve seat are indicated at 36, 37 and 38, respectively. The upper or discharge cage, valve ball and valve seat are indicated at 39, 40 and 41, respectively. The valve chambers 42 and 43 of the lower and

upper plunger valve cages are constructed substantially the same as the valve chamber 18 hereinbefore described so as to permit of the ready passage of liquid through the valve cages and immediate seating of the valve balls 37, 40 upon the beginning of the up stroke of the plunger. In Fig. 4 the tubular member 27 is directly connected by screw threads with the lower end of the working barrel 34.

The upper end of the working barrel 34 is connected by screw-threads to a guide 44 of less internal and external diameter than the working barrel, and the upper portion 45 of the plunger is of reduced diameter and slidably fits in the guide 44. The lower end of the guide 44 forms a shoulder 46 within the working barrel adapted to be engaged by an external shoulder 47 on the plunger when the plunger is pulled upwardly above its normal working stroke, thus to unseat the member 26 or 27, as the case may be, from the seat 25 when it is desired to withdraw the inserted portions of the pump or, as in some cases, raise the member 26 from the seat 25 for washing out the sand from the pump.

A frictional lock is provided to hold the working barrel in its seat 25 and this frictional lock may be of any suitable construction within the scope of the appended claims and, in this instance, is made as follows: The upper end of the guide 44 is connected by screw-threads to a compressible expandable bushing or thimble 48 of tubular construction at its ends and having any desired number of longitudinal resilient spring arms 49 connecting the tubular portions. The spring arms 49, when expanded, are accommodated in an enlargement 50 of the pump tubing, the inner face of the upper end of the enlargement constituting an upwardly and inwardly tapered shoulder 51 against which seats an upwardly and inwardly tapered shoulder or shoulders 52 on the arms 49. Thus the arms 49 yieldingly hold the working barrel toward the pump seat 25 and the arms 49 will be compressed and disengaged from the shoulder 51 by raising the plunger to cause the shoulder 47 to engage and raise the shoulder 46.

The guide 44 constitutes the inner wall of a spring chamber 53, the outer wall of said spring chamber being formed by the pump tubing. Within the spring chamber 53 is a coil spring 54 seating at one end against an external annular shoulder 55 on the guide 44, said shoulder being formed, in this instance, by the lower end of the thimble 48. The spring 54 may be and preferably is weaker than the spring 20, which is mainly relied upon to hold the thimble against the shoulder 51, and the lower end of the spring 54 bears against a wedge-shape packer 56 to press said packer into a downwardly and

inwardly tapered seat 57 formed in the pump tubing. This packer 56 serves to prevent the entrance of sand between the working barrel and pump tubing and thus 5 any sand that may be present in the liquid being pumped will not prevent or make difficult the pulling of the working barrel from the pump seat. The packer 56 also functions to hold the guide 44 concentric 10 with the working barrel so as to prevent lateral motion of the plunger adjacent the upper end of the working barrel, which lateral motion, as is well understood, would cause excessive wear of the upper end of 15 said working barrel so that sand would be admitted between the working barrel and plunger and produce excessive friction and a grinding action capable of effecting relatively rapid deterioration of the pump.

20 The guide 44 is provided with an external annular shoulder 58 formed, in this instance, by the upper end of the working barrel and adapted, when the working barrel is raised from its seat by raising of the plunger above 25 its normal working stroke, to engage the packer 56 and force said packer out of engagement with its seat 57.

The pump described above may first be installed in a well without the upper standing valve and with the imperforate tubular member 27 in place, as in Figure 4 of the drawings. It will be seen that the tubular member 27 has a larger diameter of bore than the valve cage 30, thus providing for 35 a relatively large flow of liquid through the lower standing valve and member 27 into the working barrel and thence into the pump plunger. This lower standing valve is, of course, not removable with the working barrel, being unconnected therewith. Therefore, in event of the lower standing valve becoming sanded up, the working barrel will be withdrawn from the well and the tubular member 27 removed and the valve 40 cage 30 and its parts together with the perforate member 26 substituted for the tubular member 27 as in Figure 1, and the working barrel will then be lowered to seat the member 26 within the seat 25, as in Figure 1.

45 The liquid being pumped can now readily enter the pump through the perforations 14, 28.

If the upper standing valve should sand up, the sand can be discharged or washed 50 out of the pump by raising the pump plunger sufficiently to cause disengagement of the member 26 from the seat 25, thus permitting the sand to discharge from the member 26 into the perforated portion of the 55 pump tubing, thence through the perforations 14. As soon as the sand is thus discharged, the plunger will be lowered to permit the member 26 to again engage the seat 25. Seating of the member 26 may be insured by striking the lower end of the plun-

ger against the shoulder 59 formed by the upper end of the valve cage 30, and seating of the member 27 may be insured by forcing the lower end of the plunger against the shoulder 60 formed by the upper end of the 70 member 27.

In some instances, it may be advisable to employ the pump in a well producing large amounts of gas as well as liquid, with both standing valves operating. In such event 75 the gas and liquid will pass through the lower standing valve into the member 26 and the gas will escape, before reaching the upper standing valve, through the perforations 28 and 14. Thus the gas will not interfere 80 with proper seating of the upper standing valve and plunger valves.

I claim:

1. A pump comprising pump tubing having an internal shoulder, a standing valve 85 cage provided with a valve and forming a seat, a spring between the cage and the shoulder, a working barrel, a tubular member connected with the working barrel and inserted in the seat, a friction lock between 90 the working barrel and pump tubing to hold the tubular member in its seat, and a valved plunger in the working barrel.

2. A pump comprising pump tubing having upper and lower internal shoulders, a 95 standing valve cage provided with a valve and forming a seat, a spring between the cage and the lower shoulder, a working barrel, a tubular member connected with the working barrel and inserted in the seat, a 100 spring arm connected with the working barrel and engaging the upper shoulder to hold the tubular member in its seat, and a valved plunger in the working barrel.

3. A pump comprising pump tubing, a 105 standing valve cage provided with a valve and forming a seat and mounted in the pump tubing, a working barrel, a tubular member connected with the working barrel and inserted in the seat, expandible means 110 between the working barrel and pump tubing to hold the tubular member in its seat, and a valved plunger in the working barrel.

4. A pump comprising pump tubing having an internal shoulder, a standing valve 115 cage provided with a valve and forming a seat and mounted in the pump tubing, a working barrel, a tubular member connected with the working barrel and inserted in the seat, a spring arm connected with the working barrel and engaging the shoulder to hold the tubular member in its seat, and a valved plunger in the working barrel.

5. A pump comprising pump tubing, a 125 seat-forming member mounted in the pump tubing, a standing valve cage provided with a valve and mounted in the pump tubing above the seat, a working barrel connected with the valve cage, a tubular member connected with the standing valve cage and in-

- serted in the seat, expansible means between the working barrel and pump tubing to hold the tubular member in its seat, and a valved plunger in the working barrel.
5. 6. A pump comprising pump tubing, a seat-forming member yieldingly mounted in the pump tubing, a standing valve cage provided with a valve and mounted in the pump tubing above the seat, a working barrel connected with the valve cage, a tubular member connected with the standing valve cage and inserted in the seat, expansible means between the working barrel and pump tubing to hold the tubular member in its seat, and a valved plunger in the working barrel. 70
10. 7. A pump comprising pump tubing, a seat-forming member mounted in the pump tubing, a standing valve cage provided with a valve and mounted in the pump tubing above the seat, a working barrel connected with the valve cage, a tubular member connected with the standing valve cage and inserted in the seat, a guide connected with the upper end of the working barrel of less inside diameter than the working barrel, and a valved plunger fitting in the working barrel and having a reduced portion fitting in the guide. 75
15. 8. A pump comprising pump tubing, a standing valve mounted in the pump tubing, a working barrel having a standing valve above the first standing valve, a tubular member inside of the pump tubing detachably connecting the standing valves, and a valved plunger in the working barrel. 80
20. 9. A pump comprising pump tubing, a standing valve yieldingly mounted in the pump tubing and providing a seat, a working barrel having a standing valve above the first standing valve, the second standing valve being detachably connected with the first standing valve, expansible means between the working barrel and pump tubing to hold the second standing valve toward the first standing valve, and a valved plunger in the working barrel. 85
25. 10. A pump comprising pump tubing, a working barrel in the pump tubing, a standing valve in the pump tubing, a tubular guide connected with the upper end of the working barrel of less inside diameter than said working barrel, a packer between the guide and pump tubing, an external shoulder on the guide below the packer to dislodge the packer when the working barrel is raised, and a valved plunger fitting in the working barrel and having a reduced portion fitting in the guide, and having an enlarged portion of material length fitting the working barrel below the reduced portion. 90
30. 11. A pump comprising pump tubing having a perforate portion, a standing valve mounted in the pump tubing, a working barrel having a standing valve above the
- first standing valve, a tubular perforate member connected with both standing valves and extending through the perforate portion of the pump tubing, and a valved plunger in the working barrel. 70
12. A pump comprising pump tubing having a seat, a seat-forming member mounted in the pump tubing, a working barrel in the pump tubing, a standing valve cage having a valve and connected with the working barrel, a tubular member on the valve cage engaging the last seat, a guide connected with the working barrel, a packer between the guide and the pump tubing, a spring yieldingly holding the packer in the first seat, and a valved plunger slidably fitting in the working barrel and the guide. 75
13. A pump comprising pump tubing having a seat, a seat-forming member yieldingly mounted in the pump tubing, a working barrel in the pump tubing, a standing valve cage having a valve and connected with the working barrel, a tubular member on the valve cage engaging the last seat, a guide connected with the working barrel, a packer between the guide and the pump tubing, a spring yieldingly holding the packer in the first seat, releasable means to hold the working barrel against upward movement, and a valved plunger slidably fitting in the working barrel and the guide. 80
14. A pump comprising pump tubing having a seat, a standing valve mounted in the pump tubing and providing a seat, a working barrel in the pump tubing, a tubular member connected with the working barrel and detachably engaging the second seat, a guide connected with the working barrel, a packer between the guide and the pump tubing, a spring yieldingly holding the packer in the first seat, and a valved plunger slidably fitting in the working barrel and the guide. 100
15. A pump comprising pump tubing having a seat, a standing valve yieldingly mounted in the pump tubing and providing a seat, a working barrel in the pump tubing, a tubular member connected with the working barrel and detachably engaging the second seat, a guide connected with the working barrel, a packer between the guide and the pump tubing, a spring yieldingly holding the packer in the first seat, releasable means to hold the working barrel against upward movement and a valved plunger slidably fitting in the working barrel and the guide. 105
16. A pump comprising pump tubing, a working barrel detachably connected with the pump tubing, a guide connected with the working barrel, a valved plunger slidably fitting in the working barrel and guide, and a packer between the guide and pump tubing. 110
17. A pump comprising pump tubing having

- ing a perforate portion, a seat-forming member yieldingly supported in the pump tubing, a working barrel having a standing valve, a tubular perforate member connected 5 with the standing valve and extending through the perforate portion of the pump tubing and detachably engaging the seat, a valved plunger in the working barrel, and packing means between the plunger and pump tubing above the perforate tubular member.
18. A pump comprising pump tubing having a seat, a seat-forming member mounted in the pump tubing, a working barrel in the pump tubing, a standing valve cage having a valve and connected with the working barrel, a tubular member on the valve cage engaging the last seat, a guide connected with the working barrel, a packer between the 15 guide and the pump tubing, and a valved plunger slidably fitting in the working barrel and the guide.
19. A pump comprising pump tubing having a seat, a standing valve mounted in the pump tubing and providing a seat, a working barrel in the pump tubing, a tubular member connected with the working barrel and detachably engaging the second seat, a guide connected with the working barrel, a 20 packer between the guide and the pump tubing, and a valved plunger slidably fitting in the working barrel and the guide.
20. A suitable pump comprising pump tubing having an internal seat and having 25 a shoulder above the seat, a working barrel in the pump tubing, a guide connected with the working barrel, a packer shiftably fitting the guide and fitting in the seat, expansible means connected with the guide and frictionally engaging the shoulder to hold the working barrel, and a valved plunger shiftably fitting in the working barrel and the guide.
21. A suitable pump comprising pump 30 tubing having a seat and having an internal shoulder above the seat, a working barrel having a guide, a packer slidably fitting in the guide and engaging the seat, expansible means connected with the guide and frictionally engaging the shoulder to hold the guide yieldingly secured within the pump tubing, a plunger slidably fitting in the working barrel and guide, and a valve for the working barrel.
22. A suitable pump comprising pump 35 tubing having a seat and having an internal shoulder above the seat, a working barrel having a valve connected therewith, a guide connected with the working barrel, a packer shiftably fitting the guide and detachably fitting in the seat, expansible means connected with the guide and frictionally engaging the shoulder to hold the working barrel against upward movement, a valved plunger slidably fitting in the working barrel and
- guide, and a valve for the working barrel.
23. A suitable pump comprising pump tubing having perforations and a seat above the perforations and an internal shoulder above the seat, a seat-forming member yieldingly mounted in the pump tubing below the perforations, a working barrel within the pump tubing having a guide, a packer shiftably fitting the guide, a spring yieldingly holding the packer in the first seat, 70 expansible means connected to the guide and frictionally engaging the shoulder to hold the working barrel against upward movement, a valve connected with the working barrel, and a valved plunger shiftably fitting in the working barrel and guide.
24. A pump comprising pump tubing having a seat and having an internal shoulder above the seat, a suitable working barrel within the pump tubing having a valve 80 85 within the pump tubing, a tubular guide, a packer shiftably engaging the guide, a spring yieldingly holding the packer in the seat, expansible means connected with the guide and frictionally engaging the shoulder to hold the working barrel against upward movement, and a valved plunger slidably fitting in the working barrel and the guide.
25. A suitable pump comprising pump 90 tubing having a seat and having an internal shoulder above the seat, a seat-forming standing valve cage yieldingly mounted in the pump tubing and provided with a valve, there being a perforation in the pump tubing above the standing valve cage, a working barrel within the pump tubing having a valve, a tubular perforate member connected with the last valve and with the standing valve cage and projecting into the 95 perforate portion of the pump tubing, a guide connected with the working barrel, a packer fitting the guide and detachably fitting in the first seat, expansible means connected with the guide and frictionally 100 engaging the shoulder, and a valved plunger slidably fitting the working barrel and the guide.
26. A suitable pump comprising pump 105 tubing having a seat and an internal shoul- 110 115 der, a suitable pumping mechanism in the pump tubing provided with a guide for the plunger, a packer slidably fitting the guide and detachably fitting in the seat, and expansible means connected with the guide and frictionally engaging the shoulder to hold the guide and pumping mechanism in place within the pump tubing.
27. A suitable pump comprising pump 120 tubing having perforations, a working barrel in the pump tubing, a standing valve cage having a valve and connected with the working barrel, a perforate tubular member on the valve cage, a seat-forming member mounted in the pump tubing below the per- 125 130

forations and detachably engaged by the tubular member, a guide connected with the working barrel, a packer between the guide and the pump tubing, suitable releasable means to hold the working barrel secured in the pump tubing, and a valved plunger slidably fitting the working barrel and guide.

28. A pump comprising pump tubing, a standing valve cage in the pump tubing having a valve and providing a seat, a working barrel in the pump tubing, a tubular member connected with the working barrel and frictionally engaging the seat, a guide connected with the working barrel, and a valved plunger slidably fitting the working barrel and guide.

29. A suitable pump comprising pump tubing having a seat and having perforations below the seat, a working barrel in the pump tubing having a guide, a packer slidably fitting the guide, a spring yieldingly holding the packer friction-tight in the seat, a valved plunger slidably fitting in the working barrel and guide, and a valve for the working barrel within the pump tubing.

30. A pump comprising pump tubing having a seat, a seat-forming member mounted in the pump tubing, a suitable working barrel in the pump tubing, a standing valve cage having a valve and connected with the working barrel, a tubular member on the cage detachably engaging the last seat and connected with the working barrel, a guide connected with the working barrel, a packer between the guide and the pump tubing, a spring holding the packer in frictional en-

gagement with the first seat, and a valved plunger slidably fitting the working barrel and guide.

31. A pump comprising pump tubing having a seat and having a perforate portion below the seat, a seat-forming member mounted in the pump tubing below the perforation, a suitable working barrel, a standing valve cage for said working barrel provided with a valve, a tubular perforate member connected with the standing valve cage and extending through the perforate portion of the pump tubing and in detachable relation with the seat-forming member, a tubular guide connected with the working barrel, a packer between the guide and pump tubing, a spring holding the packer in the first seat, and a valved plunger slidably fitting the working barrel and guide.

32. A suitable pump comprising pump tubing having a seat and having perforations below the seat, a standing valve cage provided with a valve and forming a seat and yieldingly mounted in the pump tubing below the perforations, a working barrel in the pump tubing having a guide, a packer slidably fitting the guide, a spring holding the packer friction-tight in the first seat, a valved plunger slidably fitting in the working barrel and guide, and a standing valve cage connected with the working barrel and having a valve and detachably connected with the second seat.

Signed at Los Angeles, Cal., this 24th day of July, 1923.

JOHN HAHN.
